UNITED STATES PATENT OFFICE.

UMBERTO MAGNI, OF LOS ANGELES, CALIFORNIA.

RADIATOR UNIT.

1,214,203.

Specification of Letters Patent. Patented Jan. 30, 1917.

Application filed August 23, 1915. Serial No. 46,902.

To all whom it may concern:

Be it known that I, UMBERTO MAGNI, residing at Los Angeles, in the county of Los Angeles and State of California, have invented certain new and useful Improvements in Radiator Units, of which the following is a specification.

My invention, which generally relates to cellular or "honey-comb" radiators of that type usually employed for cooling automobile engines, more particularly has reference to an improved radiator core or section that is composed of a plurality of longitudinal cellular units grouped together in such manner as to create between them a plurality of water passages.

More particularly my improvements relate to a construction of radiator in which the several units have shouldered or off-set 20 portions by which they are spaced apart from each other whereby to create the aforesaid water passages and thereby avoiding the use of spacing wires commonly used in radiators of the general type referred to 25 and in which the air cells or passages in each unit are formed by plaits or fins bent up from the respective side walls of the unit, the fins of one wall alternating with those of the other wall.

30 My invention, which particularly relates to the formation of the plaits or fins that form the upper and lower walls of the cells or passages and the blind water passages, and the spacing beads, primarily has 35 for its object to provide a radiator unit formed with plaits or fins having a greater cross sectional area midway the length thereof and gradually tapering from the said center toward the ends and held close 40 against each other at said ends.

Another object of my invention is to provide a radiator unit having, in connection with the tapering form of plait or fin, spacing beads having a greater cross sectional area midway the length thereof and gradually tapering toward the ends and terminating at each end some distance from the upper and lower edges of the unit, the said 45 beads alternating with the plaits.

50 With other objects in view that will hereinafter appear, my invention is an improved radiator unit that embodies the peculiar construction and novel arrangement of parts hereinafter fully described, specifically

pointed out in the claims and illustrated in 55 the accompanying drawing, in which:

Figure 1 is a front view of a conventional form of radiator in which is embodied my invention. Figs. 2 and 3 are detail perspective views of the two members or half units 60 which when united form a single unit. Fig. 4 is a cross section of a part of a radiator "honey-comb" constructed in accordance with my invention, and taken substantially on the lines 4-4 on Figs. 2 and 3. Fig. 65 5 is a similar view taken on the lines 5-5 on Figs. 2 and 3. Fig. 6 is a face view of a portion of one of the unit members and it illustrates in detail the fluid passage and the spacing bead construction. Fig. 7 is a 70 detail section taken substantially on the line 7-7 on Fig. 6.

In the drawing, 1 designates a radiator frame of the conventional form, 2 the upper feeding or receiving chamber and 3 the 75 dispensing chamber located at the bottom of the frame 1 and connected with the receiving chamber by conduits, through which the water passes from the upper to the lower chamber and which form the radiator 80 core or body.

The conduits, may be continuous from the upper to the lower chamber, but they are preferably arranged in tiers separated by auxiliary chambers 3, as indicated in 85 Fig. 1.

The radiator body or "honey-comb," (the construction of which forms the essential feature of my invention) comprises a plurality of similar units arranged side by side 90 and so shaped that a multitude of unobstructed vertical fluid passages are provided through which, the fluid to be cooled is permitted to freely flow, which also passes into the blind passages formed in the plaits or 95 fins hereinafter again referred to.

When assembling the tiers of conduits or air passages, they are suitably joined by soldering or otherwise to form a complete 100 "honey-comb" which, in the practical application of my invention, is mounted on the radiator frame in any well-known manner.

In radiators of the type hereinbefore described, the body or core is built up of blocks of conduits or passages and each of the 105 blocks embodies a number of units consisting each of two members or parts, the shape of which in my construction, and their rela-

tive cooperating position being shown in Figs. 2 and 3.

Since the two members that constitute my improved radiator unit are of like construction, a detailed description of one of such unit members will do for both.

In the development of one of the unit members, the same is formed by taking a strip of thin sheet metal of suitable length and width and providing it, by suitable means, with a number of fins or plaits 10 and a number of beads f the said beads and plaits being alternately arranged.

In my construction of plait the opening or blind passage formed in bending up the plait is of greater area at a point midway the length of the said passage, as indicated by Fig. 7, and from the said point the passage gradually tapers toward each end and is closed at the ends by reason of the two opposing walls of the plait being pressed against each other. The closed end of the plaits terminate some distance from the opposite end edges of the metal strip, as indicated by $y-y$, the reason for which will presently appear.

In the practical application of my invention, the strip of metal of which the unit member is shaped up, is preferably four inches wide and when of such width the fluid passages in the plaits are three and one-half inches long, the opposite walls at the ends being closed flat against each other to the extent of one-fourth of an inch at each end. At the center, the fluid passages are one-eighth of an inch wide and the said passages gradually taper in their width from the center to their closed ends.

The spacing beads or corrugations f that alternate with the plaits, are shaped like the blind passages, with their ends terminating in line with the ends of the blind passages,—a short distance away from the opposite edges of the strip, as is clearly shown at $z-z$.

By reason of forming the corrugations and the blind passages in the manner described and shown, a greater cross sectional area of surface is provided at the opposite ends of the air passages than at the center of said passages, as indicated by $a-a$ on Figs. 2, 3 and 6, and a sufficient beaded or corrugated surface is maintained, for holding the units separated for the water circulation.

Again, by making the corrugations or beads tapering and stopping their ends short of the opposite edges of the metal strips sufficient bearing surface is provided for holding the units separated and in addition the cooling surface between the ends of each pair of adjacent plaits is further increased as indicated at $c-c$.

To further add rigidity to the assembled radiator units the outer or bearing edges

of the fins or plaits are slightly convexed, as indicated by $10a$ (see Fig. 7) such shaping of the edges of the plaits providing for firmly seating the said edges $10a$ into the concavities f' and by reason thereof a perfect separation of the air conduits is provided, as is best shown in Fig. 5.

The edges of the units may be provided with the usual offsets $10x$ for the usual purpose of enlarging the front and rear edges 75 of the unit whereby a plurality of vertical water spaces will be formed between adjacent units when said units are grouped together side by side in a manner well understood in the art.

What I claim is:

1. In a radiator, a honey-comb structure comprising a plurality of units arranged side by side in an upright position, plaits formed on the opposite walls of each unit, 35 the plaits on one wall extending across and abutting the opposite wall, the walls between adjacent plaits being corrugated or beaded to form spacers to separate the units, the plaits having blind passages that taper 90 from the center toward the ends and terminate short of the opposite end edges of the unit, the opposite edges of the units having offsets to produce upright water passages.

2. In a radiator, a honey-comb structure comprising a plurality of units arranged side by side in an upright position, plaits formed on the opposite walls of each unit, the plaits on one wall extending across and abutting the opposite wall, the walls between adjacent plaits being corrugated or beaded to form spacers to separate the units, the plaits having blind passages that taper from the center toward the ends and terminate short of the opposite end edges of the unit, the corrugations or beads tapering in width from the center to their ends and with the said ends terminating short of the opposite end edges of the unit, the opposite edges of the units having offsets to produce 105 upright water passages.

3. In a radiator construction, a radiator unit comprising two side walls, each side wall having plaits that extend across and abut the opposite side wall, the plaits on the opposite side walls being alternately disposed, the walls between adjacent plaits being corrugated to form spacer beads for separating adjacent units, said plaits tapering in width from their center toward their 115 ends, said spacer beads tapering in width from their center toward their ends, and having their ends terminating in a line with the ends of the blind passages in the plaits, the opposite ends of said units having offsets to produce the vertical fluid passages between them for the purposes specified.

4. In a radiator, the combination with a receiving and a dispensing chamber; of a 130

radiating body comprising a honeycomb structure embodying a plurality of units arranged side by side in an upright position, 5 plaited formed on the opposite walls of the unit, the plaited on one wall extending across and abutting the opposite wall, the walls between adjacent plaited being corrugated or beaded to form spacers to separate the units, the plaited having blind passages that taper 10 from the center toward the ends and terminate short of the edges of the unit, the outer edges of said units having offsets to produce upright water passages.

5. In a radiator, a honey-comb structure comprising a plurality of units arranged side by side in an upright position, plaited formed on the opposite walls of the units, the plaited on one wall extending across and abutting the opposite wall, the walls between adjacent plaited being corrugated or beaded to form spacers, the outer edges of 15

the plaited of one wall fitting the corrugations in the opposite wall, said units having offsets for spacing the units to form the water passages. 25

6. In a radiator construction, a radiator unit comprising two side walls, two end walls connecting the side walls, each side wall having plaited that extend across and abut the opposite side wall, the plaited on the 30 opposite side walls being alternately disposed, the walls between adjacent plaited being corrugated to form spacers for separating adjacent units, said plaited and corrugations tapering in width from their centers 35 toward their ends, the plaited on the opposing walls having their outer edges shaped for closely seating in the corrugations of the said opposite walls, said units having offsets for spacing the units to form the wa- 40 ter passages.

UMBERTO MAGNI.
